(57) **CLAIM**

I claim the ornamental design of a dust cap for a support column of a bulk material belt conveyor, as shown and described.

DESCRIPTION

FIG. 1 illustrates a top view of the dust cap design in accordance with the invention.

FIG. 2 illustrates a front view of the dust cap shown in FIG. 1.

FIG. 3 illustrates a bottom view of the dust cap shown in FIGS. 1 and 2.

FIG. 4 illustrates a right-side view of the dust cap shown in FIGS. 1-3.

FIG. 5 illustrates a left-side view of the dust cap shown in FIGS. 1-4.

FIG. 6 illustrates a rear view of the dust cap shown in FIGS. 1-5.

FIG. 7 is a perspective view of the top and sides of the dust cap shown in FIGS. 1-6; and,

FIG. 8 is a perspective view of the bottom of the dust cap shown in FIGS. 1-7.

The broken lines shown in the figures are intended to show environment, but form no part of the claimed design.
